UNITED STATES PATENT OFFICE.

SAMUEL B. BRILHART, OF NEW YORK, N. Y.

CAR TRUCK.

1,417,135.

Specification of Letters Patent. Patented May 23, 1922.

Application filed February 18, 1921. Serial No. 446,016.

To all whom it may concern:

Be it known that I, SAMUEL B. BRILHART, a citizen of the United States, and a resident of the city of New York, Borough of Manhattan, in the county and State of New York, have invented a new and Improved Car Truck, of which the following is a full, clear, and exact description.

This invention relates to rolling stock and particularly to what may be termed as articulated car sections and the trucks therefor and has for an object to provide an improved arrangement of trucks which will properly support the car at all times and which will 10 properly operate regardless of the curvature of the track.

Another object of the invention is to provide a jointed car of novel structure wherein special arrangements are provided at each 20 of the end truck sections for permitting ready turning action which will co-act with the central or connecting truck section.

A still further object of the invention is to provide an improved truck wherein a 25 transverse member is provided for holding supporting rollers in place and for properly supporting a car body as the car body tilts or moves up and down.

A still further object of the invention is to 30 provide in a jointed car an improved system of rods and levers wherein the respective truck sections are positively held in correct position on a straight or curved track so that each truck section will act efficiently.

35 In the accompanying drawings—

Figure 1 is a top plan view of three interconnected truck sections and showing in dotted lines the location of the car sections therein.

40 Figure 2 is a sectional view through Figures 1 and 3, the same being taken on the line 2—2.

Figure 3 is a top plan view on an enlarged scale of one of the end truck sections shown 45 in Figure 1.

Figure 4 is a fragmentary sectional view through Figure 3 on line 4—4.

Figure 5 is a transverse sectional view similar to Figure 2 but showing a modified 50 construction.

Figure 5a is a fragmentary sectional view through Figure 5 on line 5a—5a.

Figure 6 is a fragmentary top plan view of the truck section of Figure 5.

55 Figure 7 is a fragmentary sectional view through Figure 6 on line 7—7.

Figure 8 is a top plan view showing in diagram a slight modified form of connecting rods and levers to that shown in Figure 1, one end truck section and a central truck 60 section being shown.

Figure 9 is a view similar to Figure 8 but showing another form of connecting rods and levers.

Figure 10 is a detail fragmentary view 65 through Figure 1 approximately on line 10—10, the same being on an enlarged scale.

Figure 11 is a diagram showing how the truck sections are held when passing from a straight track to a curved track. 70

Figure 12 is a diagram showing the position of the various axles of the respective truck sections when the entire car is on a curve.

Referring to the accompanying drawings 75 by numeral, 1 and 2 indicate the respective sections of the body of the car, said car sections being supported by end truck sections 3 and 4 and a central truck section 5. The car sections 1 and 2 are articulated so that they are pivotally connected at adjacent points while the opposite ends are allowed to freely swing with the truck sections 3 and 4 whereby the entire car may readily pass a straight track or a curved track having any 80 desired curvature. The particular connection illustrated in the drawing between the car sections 1 and 2 is shown more or less in detail in Figure 10 wherein it will be seen that the car section 1 is provided with ears 90 6 and 7 while car section 2 is provided with an ear 8 designed to be inserted between ears 6 and 7 whereby a pivotal pin 9 may be readily inserted through these three ears. Preferably, the openings through which pin 9 extends in ears 6, 7 and 8 are somewhat larger than the pin so that there may be a slight loose motion. In order to hold the pin 9 at a central point in respect to the truck section 5, a link 10 is provided and positioned 95 so that the pin 9 will extend through one end thereof while the opposite end is pivoted at 11 to the frame 12 and truck section 5.

By this arrangement the car sections 1 and 2 are articulated and the articulation maintained at a central point in respect to the frame 12 of truck section 5. A straight rod 13 is pivotally connected at 14 to frame 12 and also pivotally connected to a bell crank lever 15 having arms 16 and 17. The arm 16 100 is pivotally connected with a rod 18 which rod in turn is pivotally connected at 19 to

105

Figure 5a is a fragmentary sectional view through Figure 5 on line 5a—5a.

Figure 6 is a fragmentary top plan view of the truck section of Figure 5.

55 Figure 7 is a fragmentary sectional view through Figure 6 on line 7—7.

the frame 20 of truck section 3. The pivotal connection 19 is preferably at some point along the rear bar of the frame 20 while the connection 14 is preferably arranged centrally of the side bar of frame 12 of truck section 5.

A similar arrangement of levers and bars connect truck section 4 with truck section 5 so that both the front and rear truck sections are maintained at the proper angle in respect to the truck section 5. It will be noted that the angle between rod 13 and arm 17 is a 90 degree angle while the same angle is maintained between arm 16 and rod 18, though these angles may be varied if desired. The car sections 1 and 2 are provided with a number of members or arms 21 in which the various rollers 22 are pivotally mounted, there being four rollers and the rollers arranged with their axles parallel to the axle 23 of the wheels 24 and 25. By this arrangement the various rollers 22 are extending transversely of the car sections. By this construction and arrangement of rollers the car body is allowed a slight motion forwardly and rearwardly and a slight side motion as it is started and stopped and moves around a curve.

The arrangement of the rollers acts as a four point support for the adjacent ends of the car sections 1 and 2 while at the same time permits a ready and easy swinging movement of the respective sections at the same time or at different times.

The truck sections 3 and 4 are constructed differently from truck section 5 but these two end truck sections are identical so that the description of one will apply to both. As shown particularly in Figures 2, 3 and 4 the car section 1 is provided with longitudinal channel irons 27 and 28 in which the box 29 is mounted which box is provided with a depending hollow king pin 30 fitting into a pivot member 31, which pivot member is normally held centrally in a transverse sense by the springs 32 and 33 acting on the pivot member 31 and on the respective angle irons 34 and 35 riveted or otherwise rigidly secured to the curved bar 36 of the frame 20.

The pivot member 31 is provided with depending lugs 37 and 38 having horizontal axles for receiving rollers 39 and 40 which operate on suitable supporting angle irons 41 and 42 rigidly secured to the cross bars

36. Rollers 43 and 44 are mounted on the upper part of the pivot member 31 and act against small angle irons 45 and 46 also secured to the bars 36. By this construction and arrangement the king pin 30 may move laterally against the action of the springs 32 and 33 guided and supported by the rollers 39 and 40. It will, of course, be understood that this movement amounts to only a short travel. The brackets 41' and 42' prevent any undesirable upward movement of

the parts so that the rollers 39 and 40 may be always in position to properly function.

As shown in Figures 2 and 3 the angle bars 36 have what may be termed a stirrup or socket member 47 connected thereto adjacent each end. These socket members are preferably provided with enlarged portions or flanges 48 whereby they may be readily riveted or otherwise secured to the bars 36. An elliptical spring 49 is mounted on the bottom of each of these sockets and arranged so that the upper central part will engage the bottom plate 50 of a bearing member 51 which bearing member receives the axle or bearing pin 52 of roller 53 which roller engages one of the rollers 26. The sides of the bearing member 51 extend any suitable distance downwardly into a stirrup or socket member 47 so as to be guided by the stirrup in its up and down movement. This arrangement causes each of the rollers 53 to be supported by a spring and the rollers in turn support the rollers 26 which last mentioned rollers support the car body. This arrangement of support permits the sections of the car body to freely move laterally or swing around the king pin 30 co-acting with the pivot member 31 and associated parts.

In Figures 5, 5^a, 6 and 7 will be seen a modified form of the invention in which a different arrangement is shown of the stirrup or socket 47 and associated parts illustrated in Figure 2. In this arrangement of these figures there is provided a cross member or roller bar 54 which is formed with a vertical slot 55 centrally thereof accommodating the guide pin 56, which guide pin is carried in a fixed position by the channel bars 36. Each end of the roller bar 54 is provided with a socket 57 in which the respective rollers 58 are mounted, said rollers being mounted on suitable journal pins so as to freely rotate, said journal pins extending transversely of the truck section. Extending from each socket 57 is a spring engaging lug 59 through which the clamping bolts 60 extend, said clamping bolts clamping the upper part of spring 49 in place while the lower part of the spring 49 is clamped by a suitable U-bolt 61. In this way the rollers 58 are supported by elliptical springs though other forms of spring could be used.

In addition, it will be noted that the rollers 58 are permitted an up and down movement in a similar manner to the respective rollers 53, said movement being simultaneous for both rollers or alternate. The arrangement of the slot 55 and pin 56 permits the bar 54 to tilt so that one end will move down and the other up or swing in such a manner as to cause one end to stay stationary and the other to move downwardly or as a third characteristic to cause both ends to move downwardly substantially

simultaneously. As the bar 54 rocks the socket members 58 move upwardly and downwardly usually on the arc of a circle but this arc is so large and the movement is so small it is in effect a vertical movement as far as the roller 58 is concerned. Preferably, each socket member 57 is provided with guiding runners 62 which guide the socket members in their movement.

10 In Figure 8 a slight modified form of rigging is provided for holding the various truck sections at their proper angle in respect to each other and the track. It will be noted that the rods 63 and 64 are connected on opposite sides to the truck sections 3 and 5 and extend to levers 66 and 67 pivotally mounted on suitable supporting pins 65 carried by the car sections and connected together by a link 68. A similar arrangement is made at the rear of the car for taking care of the rear truck section 4 in respect to the front truck section 3 and center truck section 5.

25 In Figure 9 an additional arrangement of rigging is provided wherein the rods 63 and 64 are connected to levers 69 and 70 which levers are pivotally supported by suitable pin 69' carried by the car sections at their opposite ends and connected centrally by link 71.

30 In Figures 11 and 12 will be seen diagrams showing the action of the rods and levers illustrated in Figure 1 when the truck is passing from a straight track to a curve. 35 In Figure 11 will be seen that the rear truck section 4 is on the straight track and the axles extend at right angles to the track while the front truck section 3 is on a curve 40 and the axles extend slightly off of the line drawn normal to either rail. The axle of the center truck section 5 is at a juncture of the curve and the straight track, and consequently, is held so as to extend transversely 45 in respect to the straight track.

In Figure 12 the front and rear truck sections 3 and 4 assume the same general position while the central line through the axle of truck section 5 is a radial line in respect 50 to the curve of the track. By reason of the construction and arrangement of levers the center truck section 5 will always act as a support for the articulated section of car body adjacent the ends regardless of the 55 curve on which the car operates.

What I claim is:—

1. In a car truck a truck section frame, a car section arranged above the truck section frame, anti-friction rollers carried by the 60 car section, a roller carried by the truck section frame for each of the rollers of the car section and a roller bar for carrying the rollers mounted on the truck section frame, said roller bar being mounted so that the 65 rollers may move up and down.

2. In a device of the character described a car truck provided with a truck section frame, a car section arranged above the frame, a pair of anti-friction rollers carried by said car section, a pair of anti-friction 70 rollers carried by said frame and arranged in rolling contact with the rollers on the car section, a roller bar carrying the rollers mounted on said frame, said bar being mounted to freely move upwardly and downwardly and tilt, and cushioning means arranged adjacent each end for resiliently resisting any up and down tilting movement of said bar.

3. In a device of the character described 80 a truck section provided with a frame, a car section arranged above the truck section, spaced anti-friction rollers arranged on said car section, a roller bar arranged on said frame and provided with a vertical slot centrally, a pin fixed to said frame and extending through said slot whereby said roller bar is permitting a swinging movement around said pin and also an up and down movement, a roller arranged at each end of 90 said roller bar and with the axis at an angle to the rollers on said car section, said rollers on the roller bar being in rolling contact with the rollers on said car section and resilient means arranged adjacent the ends of 95 the roller bar acting on said frame and the roller bar for resiliently supporting the roller bar.

4. In a car truck a truck section frame, a pin extending longitudinally of said truck section frame, a roller bar having a vertical slot through which said pin extends, said roller bar having an opening adjacent each end, an anti-friction roller journaled in each of said openings, the axes of said rollers being arranged transversely of said truck section and resilient means acting on said roller bar and on said frame for resiliently supporting said roller bar.

5. In a car truck a truck section frame, a 110 roller bar extending transversely across the frame, said roller bar having openings adjacent each end, an anti-friction roller arranged in each of said openings with the axes extending transversely of the truck section and spring means acting on said roller bar adjacent each end for resiliently supporting the same.

6. In a truck of the character described a truck section frame, a roller bar extending 120 transversely of said frame and provided with openings adjacent each end, a roller arranged in each of said openings, a spring adjacent each end of the roller bar acting on the roller bar and said frame for resiliently supporting said roller bar and means adjacent the ends of the roller bar guiding the roller bar in its up and down movement.

7. In a car truck a truck section frame, a roller bar mounted transversely of said frame 130

and formed with a socket adjacent each end, an anti-friction roller arranged in each of said sockets and a spring arranged adjacent each end of said roller bar acting on the 5 roller bar and said frame for resiliently supporting said roller bar.

8. In a truck of the character described a truck section frame, a roller bar extending transversely of said truck frame provided 10 with a socket adjacent each end, a guide on each side of each socket and an extension projecting from the socket, means for preventing movement of the roller bar transversely of the truck section, said means permitting 15 a swinging and up and down movement of the roller bar, an anti-friction roller arranged in each of said sockets and a spring arranged adjacent each end of said roller bar acting on said projections and on said 20 truck section frame for resiliently supporting the roller bar.

9. In a center truck section for jointed railway cars, the combination of two car sections and means connecting them together, 25 of a truck section frame beneath the connected portions of the car sections, means associated with the car sections and the frame serving to prevent lateral shifting of the car sections with respect to the frame, said last 30 mentioned means comprising a link, one end of which is pivoted to the side of the frame and the other end of which is pivoted to the coupling pin between the car sections.

10. In a car of the character described a 35 pair of car sections, means for pivotally connecting said sections together, a central arranged truck section supporting adjacent ends of car sections, a pair of end truck sections, a rod pivotally connected to said central truck sections on each side thereof, said rod extending in opposite directions toward the end truck sections, a bell crank lever for each of said rods pivotally supported on said body sections and pivotally connected with 45 said rods and a second pair of rods pivotally connected with said bell crank levers and also pivotally connected with the respective

ends of said end truck sections whereby the axles of the respective truck sections are maintained at a proper angle in respect to 50 the track as the car moves over both a straight and curved track section.

11. In a car of the character described a car section, a pair of anti-friction rollers arranged on the car section with their axes extending substantially longitudinally of the car section, a truck section provided with a frame, a pair of stirrups or socket members supported by said frame, a pair of bearing members resiliently supported in each of 60 said socket members and an anti-friction roller carried by each of said bearing members, said anti-friction rollers being arranged in rolling contact, the rollers carried by the car section and also with their axes 65 extending transversely of the car section.

12. In a car of the character described a car section, a truck section provided with a frame, anti-friction members interposed between the car section and the truck section, 70 means connected with the car section forming a king pin, a pivot member having an opening for receiving said king pin, anti-friction means supporting said pivot member so as to permit the pivot member to be 75 moved in a transverse plane and resilient means acting on the pivot member and along said frame for resisting said transverse movement.

13. In a car truck a truck section frame including a pair of transverse spaced bars, anti-friction means mounted on said bars for supporting the car section, resilient means for supporting said anti-friction means, a king pin receiving pivot members arranged between 85 said transverse bars, a plurality of anti-friction means carried by said pivot member, guides for guiding said anti-friction members as said pivot member moves transversely of the truck section frame and a spring arranged on each side of said pivot member for resiliently holding the same in a 90 central position.

SAMUEL B. BRILHART.
